EMULSION TANK AND STAIN ROLL

Leo Gariepy, Woonsocket, R. I.

Application October 3, 1939, Serial No. 297,754

2 Claims.

(Cl. 68—203)

This invention relates to emulsion tanks, and more particularly to the construction of the stain roll forming a part thereof.

The primary object of the invention is to provide a stain roll constructed in such a way as to cause the stain contained in the tank, to flow throughout the length of the roll, insuring an even staining of the material under treatment.

Another object of the invention is to provide a stain roll of this character which will agitate the stain, during the staining operation, thereby maintaining the stain thoroughly mixed during the staining operation.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a plan view of a tank constructed in accordance with the invention, the stain roll thereof being mounted in the tank.

Figure 2 is a sectional view taken on line 2—2 of Figure 1.

Figure 3 is a front elevational view of the emulsion tank.

Figure 4 is a rear elevational view thereof.

Referring to the drawings in detail, the tank is indicated generally by the reference character 5, the tank being provided with bearings 6 formed in the end walls thereof, for the reception of the shaft 7 on which the roll of the apparatus, is mounted, the roll being indicated by the reference character 8.

As clearly shown by the drawings, the roll is provided with enlargements 9 that are substantially wide, and extended throughout the length of the roll 8. These enlargements 9 are formed with longitudinal grooves 10 to pick up the stain contained in the tank, as the roll rotates.

As clearly shown by Figure 1 of the drawings, the enlargements 9 are arranged at oblique angles with respect to the ends of the roll to the end that the stain or material used in dyeing the wool under treatment, is caused to move rapidly, from one end of the tank to the other, as the roll is being rotated. It will be further seen that due to this construction, the grooves will pick up the stain which will gravitate towards the low ends of the grooves, thoroughly

mixing the stain, and preventing the stain from remaining in one spot on the material.

Mounted on one end of the shaft 7 is a pulley 11 over which a belt from a suitable power mechanism not shown, operates to rotate the shaft and roll mounted thereon.

Stationary arms indicated at 12 extend upwardly from the rear wall of the tank, and provide a support for the shaft 13 on which the tube 14 operates, the tube 14 being provided with division disks 15 dividing the tube into a plurality of spools, from which the wool being dyed or stained, is fed to the roll.

Set screws indicated at 16 extend through the bearings 17 at the ends of the shaft 13, for holding the shaft 13 in various positions of adjustment.

At the opposite side of the tank are spaced upstanding fingers 18 between which the wool under treatment moves, from the machine. These fingers 18 prevent lateral movement of the wool as it passes from the tank to insure against the wool becoming tangled or matted, during the staining treatment.

In view of the foregoing detail description, a further description as to the operation and use of the apparatus, is believed to be unnecessary.

What is claimed is:

1. A device for staining wool, comprising a tank 30 adapted to contain a staining liquid, a roll mounted for rotary movement within the tank, members having wide outer surfaces formed with shallow grooves mounted on the periphery of the roll and extending appreciable distances therefrom, 35 said grooved members being disposed spirally of the roll, the grooves being adapted to pick up liquid from the tank and deliver the liquid above the tank as the roll rotates, and means for feeding yarn over said members, whereby the yarn 40 becomes saturated with the staining liquid contained in the grooves.

2. A device for staining wool, comprising a tank adapted to contain a staining liquid, a roll mounted for rotary movement within the tank, 45 members having wide outer surfaces mounted on the periphery of the roll and being extended appreciable distances beyond the roll, the outer surfaces of said members being generally flat and formed with shallow grooves, said grooves being 50 adapted to pick up liquid from the tank and deliver the liquid above the tank as the roll rotates, said grooved members being spirally arranged on said roll, and means for feeding and guiding strips of yarn over said grooved members to pick up stain retained in said grooves.

LEO GARIEPY.
